SPRAY DEVICE

Donald P. Hunter, Los Angeles, Calif., assignor to
 Turco Products, Inc., Los Angeles County,
 Calif., a corporation of California

Application June 16, 1941, Serial No. 398,216

4 Claims. (Cl. 299—83)

My invention relates to improvements in spray devices and is a continuation in part of my copending application Serial No. 360,022, filed October 7, 1940, now issued as Patent No. 2,295,661, Sept. 15, 1942, entitled Method and apparatus for spraying liquid.

In my said copending application I illustrate and claim a spray device particularly adapted for vehicle washing operations in which, during a part of the operation, a chemical cleaning solution is admixed with the main fluids such as air and water and in which, during other parts of the operation, it is desired to wash or rinse with fluid free of the cleaning solution. The device of my said copending application comprises a structure in which the chemical solution is introduced to the main fluid passage of the device by means of suction on an aspirating orifice induced by flow of fluid through the device, said orifice being controlled by a check valve seating away from the main fluid passage—that is, seating towards the source of the solution, the check valve being operated by the pressure differential between the main fluid passage and the solution reservoir.

I have found that in using said device operators frequently open the air line to the spray device at the outset without immediately opening the water line. This induces a vacuum on the aspirating orifice which causes the chemical solution to be drawn from the reservoir and deposited in concentrated state on the article being washed, such for instance as an automobile, without initial admixture with water, and the undiluted chemical solution thus deposited sometimes spots the article being washed.

It is therefore an object of my present invention to overcome this objection and this I do by substituting for the check valve element shown in the combination of my said copending application, an improved check valve having a double seat—that is, a seat both towards the inlet and one towards the outlet end of the chemical solution line and by selecting a ball valve of a weight commensurate with the optimum vacuum on the aspirating orifice.

Other objects and accomplishments of my improvements will become obvious from the following detailed description of a presently preferred embodiment thereof, for which purposes I shall refer to the accompanying drawing in which the figure is a longitudinal section view, partly in elevation.

Referring now to the drawing, I show at 5 a body having a handle portion 6 and a barrel portion 7, so designed as to be conveniently held in one hand by the operator, there being a projection 8 at the rear of the handle near the top for engagement by the top edge of the hand to act as a stop—that is, in use, the handle some-

times becomes wet and slippery and the projection 8 prevents such slippage. An opening 9 on the top of the barrel serves for hanging purposes. Within the handle portion, I provide a longitudinal water passageway 15 and an air passageway 16. Passageway 15 communicates tangentially at its discharge end with a passageway 17 extending longitudinally in the barrel, passageway 17 being of a relatively larger diameter than

10 is the diameter of passageway 15. A plug 25 is screwed into a threaded bore 26 in the body, said plug having a head 27 for the reception of a wrench or tool. Plug 25 has, in register with passageway 16, an annular groove 28 and from the bottom of this groove a reduced passageway 30 communicates with a relatively larger longitudinal central bore 31 which is enlarged at 32, said enlarged portion being internally threaded to receive the inlet end of an air passing tube 33. Tube 33 extends longitudinally and concentrically of passageway 17 and terminates short of the outer end of said passageway to provide an expansion chamber 35. Tube 33 reduces the cross-sectional area of passageway 25 17 inwardly from the chamber 35. A nozzle tube 40, which is tapered to flare outwardly at its inner end 41 and its outer end 42, is threaded into the discharge end of passageway 17, the inner end 41 terminating short of the discharge end of tube 33 to provide the expansion chamber 35 therebetween. The bore of tube 40 is relatively smaller in diameter than passageway 17 whereby to provide a restricted discharge outlet.

An adapter 50 is threaded at its upper end 51 into threaded opening 52 in the bottom of barrel 7, there being threaded into the lower end 54 of the adapter another adapter element 55 through which a central bore 56 is provided. A tube 60 is threaded at its top end into bore 56 and extends 40 at its lower end into the solution container 45 and is internally threaded at its bottom end 61 to receive an adjusting screw 62 adapted to cover and uncover reduced opening 63 in the side wall of the tube.

45 Adapter 50 has a central bore 65 provided through division wall 67, the upper face of said wall affording a seat around opening 65 for ball valve 70. An externally threaded ring 72 is screwed into the top end of adapter 50 to provide an upper seat 75 for ball valve 70. A screen 80 is confined against the top of ring 72 by an upper externally threaded ring 81. Slots 83, 84, respectively, are provided in the top of rings 72, 81 for reception of a tool to remove and replace the rings. A lower screen 85 is confined against the bottom face of wall 67 by ring 87 and the upper end of adapter element 55.

The container 45 is mounted under the spray device by the reduced lower end of adapter element 55 extending through a hole in the cover

cap 88 of the container, the cover cap being confined against shoulder 56a by an internally threaded collar 89 screwed onto adapter element 55.

For connecting my spray device with the water and air or other fluid sources, I provide manual control valve members 90, 91, which may be of any suitable construction, valve member 90 being connected at its outlet end into the inlet end of passageway 15 and at its inlet end it is connected to the water supply hose 93 for supplying water under pressure. Valve member 91 is connected at its outlet end into the inlet end of passageway 21 and at its inlet end to the air supply hose 94 for supplying air under pressure.

For insuring the proper amount of water feed through valve 90 to provide a predetermined mixture of solution from container 45, I show a stop member comprised of a bracket 95 having a right angle arm 96 through which there is provided a threaded opening to adjustably receive screw 97 against whose outer end 97a valve operating handle 98 abuts when valve 90 is opened to the desired extent. For fully opening valve 90 handle 98 is swung in the opposite direction (counterclockwise) until the valve is opened fully or to the extent desired.

The operation of my device is as follows: A supply of liquid cleaning solution is placed in container 45, which is exposed to atmosphere through opening 35, and air valve 91 is substantially fully opened and water valve 90 initially slightly opened. The air under pressure discharging from the outlet end of tube 33 directly into the discharge tube 40 will induce a vacuum on the ball valve 70 to lift it from its seat to permit cleaning solution to be drawn in and admixed with the water and air before being finally discharged. In constructing my device, I first determine what vacuum will draw in the chemical solution at the desired rate and then I select a ball 70 of a weight sufficient to prevent it from being drawn against upper seat 75 so long as that optimum vacuum is not exceeded.

The internal diameter of tube 40 is such that it will freely pass all fluid discharged from tube 33 and thus induce sufficient vacuum on ball 70 to move it off its lower seat and such that if the valve 91 is fully opened without water valve 90 being opened at all, an excess of vacuum will be exerted on ball 70 causing the ball to be moved and held against its upper seat. This prevents the possibility of an operator using the device to deposit undiluted cleaning concentrate on the vehicle. It is therefore preferable to open water valve 90 slightly, or until handle 98 abuts stop 97a, simultaneous with the opening of air valve 91. The resultant introduction of a relatively limited flow of water through passageway 17 will correspondingly tax the capacity of outlet 40, reducing the vacuum sufficiently to prevent the ball 70 from being drawn against its upper seat, thus permitting the desired amount of cleaning solution to be drawn in from container 45. When it is desired to rinse the vehicle being washed, without the presence of any cleaning solution, it is only necessary to further open valve 90 to admit a greater volume of water under pressure through passageway 17, which greater volume will so tax the capacity of outlet 40 as to destroy the vacuum or cause back pressure on ball

70. When such a situation exists, ball 70 will prevent any of the air or water from entering the container 45 by seating against its lower seat.

5 While in the foregoing I have described specific proportions and associations of parts which I have found desirable for particular uses, I wish it understood that various modifications and adaptations may be made therein within the 10 broader scope and spirit of my invention as defined by the appended claims.

I claim:

1. A spray device comprising, in combination, a body, a passageway therein for passing fluid under pressure, a restricted outlet disposed concentrically in the discharge end of the passageway, a tube for passing fluid under pressure, said tube being mounted concentrically in the passageway and having its discharge end adjacent the inlet end of the restricted outlet, an aspirating conduit in the body and having its inlet communicating with a fluid supply and its outlet communicating with the passageway at a point inwardly from the restricted outlet, a check valve 25 in the conduit, and means providing seats for said check valve both towards and away from the outlet end of the conduit, said valve being operable by virtue of pressure differential between the respective ends of the conduit.

30 2. A spray device comprising, in combination, a body, a passageway therein for passing fluid under pressure, a restricted outlet disposed concentrically in the discharge end of the passageway, a tube for passing fluid under pressure, said 35 tube being mounted concentrically in the passageway and having its discharge end adjacent but spaced inwardly from the restricted outlet, a solution reservoir, an aspirating conduit having its inlet communicating with said reservoir and 40 its outlet communicating with the passageway at a point spaced inwardly from the discharge end of the tube, a check valve in the conduit, means providing seats for said check valve both towards and away from the outlet end of the conduit, said 45 valve being operable by virtue of pressure differential as between the respective ends of the conduit, and means for regulating flow of fluid through the passageway.

3. A spray device comprising, in combination, 50 a body, a passageway therein for passing fluid under pressure, an aspirating conduit in the body communicating at its outlet end with the passageway and its other end with liquid under atmospheric pressure, means for introducing a controlled stream of fluid under pressure through said passageway whereby to induce a controlled vacuum on the outlet end of said conduit and a ball valve in the conduit seating towards the passageway, said ball valve being of a weight corresponding to the optimum vacuum desired to be maintained on the outlet end of the conduit whereby to remain unseated by virtue of its own weight until said vacuum exceeds said optimum.

4. The combination of claim 1 which includes 65 a valve controlling the inlet end of said passageway, a manual operating handle on the valve and an adjustable stop element mounted on the body in position to stop valve opening movement of said handle at a predetermined point.
